UNITED STATES PATENT OFFICE.

HUGH W. BATCHELIER, OF WORCESTER, MASSACHUSETTS.

LAMP HOLDER FOR AUTOMOBILE HOODS.

Application filed November 28, 1922. Serial No. 603,776.

To all whom it may concern:

Be it known that I, HUGH W. BATCHELIER, a citizen of the Dominion of Canada, residing at Worcester, in the county of Worcester and State of Massachusetts, have invented new and useful Improvements in Lamp Holders for Automobile Hoods, of which the following is a specification.

This invention is embodied in an improved holder, adapted to support an incandescent electric lamp within an automobile hood, and to separably and adjustably engage the usual pintle rod which extends centrally along the top portion of the hood from front to rear, above the engine, the hood sections being hinged to this rod. There is sufficient space between the pintle and the engine to contain a lamp supported by the pintle, in position to illuminate the engine.

My improved holder enables the lamp to be connected with the pintle with the axis of the lamp substantially at right angles with the pintle, and either in a vertical position directly under the pintle, or inclined toward either side of the hood, the attachment being adjustable lengthwise of the pintle, toward and from either end of the hood.

Of the accompanying drawings forming a part of this specification,—

Figures 1 and 2 are side elevations, showing a holder embodying the invention, and a portion of the pintle rod, the latter being shown in side elevation by Figure 1, and in transverse section by Figure 2.

Figure 3 shows in perspective the holder members shown by Figures 1 and 2, separated from each other.

Figure 4 shows the lamp partly in section, and partly in elevation, separated from the holder.

The same reference characters indicate the same parts in all the figures.

In the drawings, 12 represents a portion of the usual cylindrical pintle rod in the upper portion of an automobile hood. The pintle forms an element of a hinge connection between the fixed and movable parts of the hood and is spaced above the engine, a considerable portion of its periphery being unobstructed, so that the holder hereinafter described is adapted to slide upon the pintle toward either end of the hood.

My improved holder is adapted for use with an incandescent electric lamp, of which 13 is the bulb, the lamp having a shank 14,

coaxial with the bulb, the holder being adapted for frictional engagement both with the pintle 12 and the shank 14, and to hold the lamp with its axis substantially at right angles with the pintle.

The holder includes two members 15, preferably pressed from sheet or plate metal. Said members include lower clamping jaws 16, formed to embrace and frictionally grasp the shank 14, upper clamping jaws 17, formed to frictionally grasp the pintle 12, and necks 15, connecting the said jaws. The holder also includes clamping means such as headed bolts 18, inserted in perforated ears 19 at opposite ends of the lower jaws, and provided with nuts 20, for exerting clamping pressure on the lower jaws, and means such as a headed bolt 21, inserted in orifices 22 formed in the neck 15, and provided with a wing nut 23, for exerting clamping pressure through the necks on the upper jaws. The orifice 22 in one of the necks 15, is preferably square, as shown by Figure 3, and receives a squared portion of the bolt 21, to prevent the latter from turning.

The grasping faces of the upper jaws 17 are formed to extend parallel with the axis of the pintle, and to bear on opposite sides thereof. The grasping faces of the lower jaws 16 extend at right angles with the grasping faces of the upper jaws, so that the axis of the lamp is maintained at right angles with the axis of the pintle.

The upper jaws 17, when released from clamping pressure, are adapted to slide lengthwise of the pintle, so that the holder may be adjusted toward either end of the hood, as indicated by full and dotted lines in Figure 1. Said jaws are also adapted to turn on the pintle, and cause the axis of the lamp to stand either vertically under the pintle, as shown by full lines in Figure 2, or at an inclination, as shown by dotted lines.

When the nut 23 is tightened, the upper jaws firmly engage the pintle, and confine the lamp in any position to which it may be adjusted. Provision is therefore made for illuminating practically any part of an engine located under the pintle 12. Owing to the fact that the lower jaws 16 extend at right angles with the upper jaws 17, the holder is permitted to swing only in a plane at right angles with the pintle, and is prevented from swinging in any other direction, so that the lamp is firmly supported in each

of the positions to which it may be adjusted, by a holder composed of two one-piece members and clamping means connecting said members.

6 The lamp preferably includes a reflector 25, and the preferred lamp structure is as shown by Figure 4, the shank 14 being a tube integral with or fixed to the reflector. The shank, therefore, constitutes a socket 10 with which the base or neck 13^a to which the bulb is attached, may be detachably connected by well known means, such as the bayonet-joint connection shown by dotted lines in Figure 4. The tubular shank constitutes also a holder in which the usual insulating plug 26 is fixed, said plug having sockets 27 for the usual conducting wires, and binding screws 28, to confine said wires.

I claim:

20 A lamp holder of the character referred to comprising two similar members each shaped at one end to form one of a pair of

complemental jaws and having its other end offset inwardly from the body of the member and terminating in oppositely projecting ears, the surface of the offset portion of each member, between said ears, being transversely curved, whereby when the members are in operative relation said curved sections will closely embrace the shank of an electric lamp and the ears will project radially outward therefrom at substantially diametrically opposite points, means connecting the ears on the members to retain them in engagement with the shank of a lamp, and means connecting the members and adapted to draw the complementary jaws into engagement with a suitable support and retain them in such relation for the purpose described.

In testimony whereof I have affixed my signature.

HUGH W. BATCHELLER.
